Primary Examiner — Mary Ann Calabrese(74) Attorney, Agent, or Firm — Fredrikson & Byron, P.A.(57) CLAIM

The ornamental design for a dining table, as shown and described.

DESCRIPTION

FIG. 1 is a top front perspective view of a dining table showing my new design;

FIG. 2 is a front elevational view thereof, the rear elevational view being a mirror image thereof;

FIG. 3 is a side elevational view thereof, the opposite side elevational view being a mirror image thereof;

FIG. 4 is a top plan view thereof; and,

FIG. 5 is a bottom plan view thereof.

The appearance of any portion of the dining table between the break lines forms no part of the claimed design.

1 Claim, 5 Drawing Sheets(56)
